UNITED STATES PATENT OFFICE.

CHARLES A. SUTLIFF, OF DETROIT, MICHIGAN.

POULTRY LAMP.

1,411,758.

Specification of Letters Patent.

Patented Apr. 4, 1922.

Application filed March 30, 1921. Serial No. 457,081.

To all whom it may concern:

Be it known that I, CHARLES A. SUTLIFF, a citizen of the United States, residing at Detroit, in the county of Wayne and State 5 of Michigan, have invented a new and useful Poultry Lamp, of which the following is a specification.

This invention relates to lamp constructions and more particularly to a lamp especially designed for use in poultry houses or the like it being the primary object of the invention to provide a lamp having novel means for causing the same to illuminate the surrounding area at predetermined 15 intervals.

A further object of the invention is to provide a movable hood associated with the burner for covering the burner to eliminate any possibility of the light rays being projected therefrom.

A still further object of the invention is the provision of a combined hood and reflector, whereby the lamp may be supported in a convenient location as from the ceiling 25 of a poultry house, the combined hood and reflector acting to reflect the light rays downwardly.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed, may be made within the scope of what is claimed, without departing from the spirit of the invention.

Referring to the drawings:—

Figure 1 illustrates a side elevational view 40 of a lamp constructed in accordance with the present invention, the combined hood and reflector being shown in section while the base of the lamp is partly broken away;

Figure 2 illustrates a fragmental sectional view through the body portion of the lamp, showing the spring controlled actuating means;

Figure 3 illustrates a sectional view taken on line 3—3 of Figure 1;

Figure 4 illustrates a sectional view showing the controlling pinion as secured to the operating rod;

Figure 5 illustrates a sectional view taken on line 5—5 of Figure 4.

Referring to the drawings in detail, the lamp includes an upper portion including a

combined hood and reflector, the same being illustrated by the reference character 5, and as shown, the concaved surface thereof is covered with a suitable reflecting material 60 to cause the light rays from the lamp, to be hereinafter more fully described and which is supported under the concaved surface, to be reflected downwardly.

The member 5 is preferably circular in 65 plan and is provided with a central upwardly extending circular flange 6, that is apertured at predetermined intervals to provide a ventilator for the hood, and at the same time provide means for connecting the 70 supporting hook 7 to the hood.

The lower section of the lamp includes a casing 8 in which is supported the operating mechanism of the lamp, the casing acting as a support for the oil tank 9 which has the 75 burner 10 supported at the upper end thereof, the burner being of the usual construction and provided with a wick and operating means.

Surrounding the tank 9 is a tubular guard 80 11 formed preferably of asbestos, the guard being of a length equal to the combined length of the tank and burner, there being provided lugs 12 on the guard 11, adjacent to the bottom thereof, which lugs have connection with the operating rod 13, the rod 13 at one side of the guard 11 being threaded to operate through the pinion 14, while the rod 15 acts as a guiding rod to insure the true movement of the guard 11. 90

Supported at the upper end of the tubular guard 11, is a reflector 16 which has a concaved upper surface to reflect the light rays from the burner 10 upwardly, where the same contacts with the reflecting surface of the 95 section 5 which bends the light rays downwardly to illuminate the surrounding area.

The upper and lower sections of the lamp are connected by means of the rods 17 and by means of which the lower section is supported in proper relation with the upper section or hood 5. The operating means which is supported within the casing 8 is of the spring motor control type, and comprises a main shaft 18 which supports the sleeve 18' that is revolved by the main spring 19, the sleeve 18' having a pinion 20 on one end thereof, that meshes with the pinion 21 carried by the shaft 22 which has one end thereof supported by the bracket 23, and the opposite end supported by the bracket 24. 105 110

On one end of the shaft 22 is mounted a

disk 25 to which is eccentrically connected the arm 26 that has its lower extremity connected to the lever 27 which in turn is connected to the lever 28, there being provided a slot in the lever 27 to accommodate a pin carried by the lever 28, to permit of movement of the lever 28 with respect to the lever 27.

The levers 27 and 28 have pivotal connection with one wall of the casing 8 and the lever 28 has pivotal connection with the sleeve 29 that is mounted to reciprocate on the shaft 18 the ends thereof cooperating with the beveled pinions 30 and 31, which are moved in one direction by means of the coiled spring 32 associated therewith.

A spring member 33 connects the levers 27 and 28 to cause the levers to move more readily under the influence of the main spring 19. Mounted within the casing is the shaft 34 which has a threaded portion cooperating with the threads of the pinion 14, whereby movement of the shaft 34 results in a relative movement of the pinion 14 which in turn imparts a vertical movement to the controlling rod 13 to move the guard 11 longitudinally of the burner.

Supported on the shaft 34 is a disk 35 which moves longitudinally of the shaft by means of the governor 36 and governor weights 37, which weights expand the springs, under the centrifugal force of the shaft to a point where the disk 35 contacts with the feet 38 of the controlling member, it being understood that the shaft 34 receives its power from the pinion 39 carried on one end thereof, and which is automatically thrown into mesh with one of the pinions 30 and 31 according to the direction of rotation of the shaft 34.

It is to be understood that the gearing is so timed that by setting the device, the tubular guard 11 will be moved to shut off the light rays from the burner, and permit the light rays to be projected upwardly to the reflecting surface of the hood 5 at predetermined intervals.

In the operation of the device, assuming that the gear operating mechanism as shown by Figure 2 of the drawings, is such as will cause the threaded rod 13 to move downwardly, bringing with it the tubular guard 11, it is obvious that as the disk 25 is rotated, the levers 27 and 28 are moved to a position as indicated in dotted lines in

Figure 2, whereupon the upper end of the sleeve 29 moves out of contact with the pinion 30 and the coiled spring 32 at the upper end thereof forces the pinion 30 into mesh with the pinion 39, whereupon the pinion 39 is rotated in the opposite direction to move the threaded rod 13 in the opposite direction.

When the sleeve 29 is moved downwardly, the lower extremity thereof engages the pinion 31 and moves the same against the tension of the spring 32, thus disengaging the pinions 31 and 39 leaving the pinion 30 at the upper end thereof to rotate the pinion 39.

Having thus described the invention, what is claimed as new is:—

1. A lamp comprising a hood having a lower concaved reflecting surface, a casing means for supporting the hood and casing in spaced relation, a lamp supported by the casing, a tubular guard surrounding the lamp, a reflector supported at the upper end of the guard for directing the light rays of the lamp to the concaved surface of the hood, and means for moving the guard to cover and uncover the lamp.

2. A lamp comprising a hood having a lower reflecting surface, a casing supported under the hood, a burner mounted on the casing, a guard surrounding the burner and adapted to move thereover, means for moving the guard to a position in close proximity with the hood, said means adapted to move the guard to a position to permit the light rays to project therefrom, and a reflector carried at the upper end of the guard for directing light rays to the hood.

3. A lamp comprising a hood having a reflecting surface, a casing supported under the hood, a lamp on the casing, a tubular guarding member operating over the burner, said guarding member being formed of asbestos material, a reflector disposed at the upper end of the guarding member, and means for moving the guarding member over the burner.

In testimony that I claim the foregoing as my own, I have hereto affixed my signature in the presence of two witnesses.

CHARLES A. SUTLIFF.
